(No Model.)

H. E. SMITH.
CENTRIFUGAL MACHINE.

No. 519,975.

Patented May 15, 1894.

Fig. 1.

UNITED STATES PATENT OFFICE.

HAMILTON E. SMITH, OF NEW YORK, N. Y.

CENTRIFUGAL MACHINE.

SPECIFICATION forming part of Letters Patent No. 519,975, dated May 15, 1894.

Application filed January 18, 1894. Serial No. 497,310. (No model.)

To all whom it may concern:

Be it known that I, HAMILTON E. SMITH, a citizen of the United States, residing at New York, in the county of New York and State 5 of New York, have invented new and useful Improvements in Centrifugal Machines, of which the following is a specification.

This invention relates to that type of centrifugal machines particularly designed for 10 use in laundries to extract water or moisture from clothes, but useful for many other purposes, wherein a balance or regulator spring is employed to render the rotary drum susceptible of yielding laterally, or in the plane 15 of rotation, and to restore the center of gravity of the drum, and the perpendicularity of the drive-shaft.

The object of the present invention is to 20 provide new and improved means whereby the balance or regulator spring is housed within an attachment on the bottom wall of the stationary cylinder or case, thus rendering the machine strong, substantial and durable.

The invention also has for its objects to 25 provide novel devices whereby the bearing for the drum-shaft can be readily renewed without disturbing the operative connection of the spring with the cylinder or case; and to provide novel and simple means whereby the air 30 currents flowing down, or descending, through the rotary drum will not encounter or obstruct the air currents ascending between the drum and the cylinder or case.

To accomplish all these objects, the invention 35 consists in the features of construction and the combination or arrangement of parts hereinafter described and claimed, reference being made to the accompanying drawings, in which—

40 Figure 1 is a vertical central sectional view of a centrifugal machine embodying the invention. Fig. 2 is a horizontal sectional view taken on the line 2—2, Fig. 1; and Fig. 3 is a similar view taken on the line 3—3, Fig. 1.

45 In order to enable those skilled in the art to make and use my invention, I will now describe the same in detail, referring to the drawings, wherein—

The numeral 4 indicates a cylinder or case 50 composed of sheet iron, or any other material suitable for the conditions required, and having a bottom wall 5 which is secured in posi-

tion in any desired manner, and is provided with supporting legs or standards 6 for sustaining the cylinder or case in a stationary 55 position while the internal perforated drum 7 is rapidly revolving. The bottom wall of the cylinder or case is preferably composed of a casting, and is formed at its center with a circular orifice surrounded by an upwardly 60 projecting flange 8. The central opening in the bottom wall serves to receive a circular housing or boxing 9, preferably composed of a casting and having at its top portion a lateral flange 10 resting on the bottom wall 5 and 65 bearing against the flange 8, the construction being such that the housing or casing can be readily removed if occasion demands. The housing or casing is hollow, and is provided with a cover-plate 12, preferably secured in a 70 fixed position by providing the housing or casing with recesses 13, Fig. 2, with which engage radial projections 14 at the edge of the cover-plate 12. The vertical drive-shaft 15, to the upper end of which the perforated drum 75 is rigidly attached, is provided at its lower end with a ball 16, fitting a ball-socket 17 in a stationary bearing 18, for the purpose of permitting the vertical shaft to swing or oscillate on the bearing as a pivot while the 80 drum and shaft are rapidly revolving. The shaft is provided with an adjustable collar 19, adapted to lie in proximity to the bottom wall of the housing or casing 9 for preventing vertical displacement of the shaft. In the center of the housing or casing 9 is arranged a sleeve 20, having a flanged upper end which rests upon a convolute spring 22, the inner end of which is rigidly secured to the sleeve, while the outer end is rigidly secured to the 90 housing or casing. The spring, resting upon the bottom wall of the housing or casing, is thus firmly supported while it can yield in a horizontal plane. A bushing 23 is arranged within the sleeve, and is provided with a 95 flanged upper end resting upon the upper end of said sleeve, the construction being such that the bushing can be readily removed for the purpose of introducing a new bushing whenever necessary for the purpose of maintaining a perfect bearing for the rotary drive-shaft. The cover-plate 12 of the housing or casing 9 is provided with a central opening, into which the hub of the perforated drum 100

may project if desired, as clearly shown in Fig. 1, so that the hub retains the bushing from vertical displacement. The bushing is designed to be stationary in the sleeve while the shaft rotates in the bushing.

In the practical operation of a centrifugal machine, it is desirable to render the drum susceptible of yielding laterally or horizontally, to avoid excessive strains; and this is accomplished by my invention, while the center of gravity of the drum and the perpendicularity of the drive-shaft are restored. The improved construction and arrangement described and shown provide means whereby the balance or regulator spring is housed in and supported by an attachment on the bottom wall of the stationary cylinder or case, which is advantageous in that it renders the machine strong, substantial and durable. The removability of the bushing is advantageous, in that the sleeve being attached to the spring cannot be readily removed and replaced; and without the bushing it is difficult to maintain a perfect bearing for the rotary shaft. By providing the sleeve, which is attached to the spring with a removable bushing, I am enabled to conveniently renew the bushing without disturbing the operative connection of the spring with the cylinder or case.

The top end of the sleeve or drum is provided with an attached ring or annulus 24, which overhangs the drum, and the upper end of the cylinder or case is provided with a ring or annulus 25, which overhangs the cylinder or case. The diameter of the ring 25 is considerably greater than the diameter of the ring 24, and said ring 25 is supported above the top edge of the cylinder or case through the medium of brackets or arms 26, in such manner as to provide a surrounding air exit 27, for the ready escape of the air ascending between the drum and the cylinder or case. By constructing the ring 24 so that it will stand in a horizontal plane, or substantially so and overhang the drum, and arranging the ring 25 of greater diameter in the manner explained, the air currents flowing down or descending through the rotary drum, will not encounter or obstruct the air currents ascending between the drum and the cylinder or case, whereby the machine is rendered very effective and desirable in practical operation. The vertical drive-shaft may be rotated in any ordinary manner; and, as the particular method of rotating the shaft constitutes no part of my invention, I do not deem it necessary to further describe the same. As the convolute spring is housed within the housing or casing applied to the bottom wall of the cylinder or case, the spring is not only

properly supported from vertical displacement, but it is effectually protected; and this is a desirable feature in centrifugal machines having a balance or regulator spring attached.

Having thus described my invention, what I claim is—

1. In a centrifugal machine, the combination with a rotary drum, and a drive-shaft therefor, of a cylinder or case having its bottom wall provided with a housing or casing which is solely supported thereby, a sleeve arranged in the housing or casing, and a convolute spring located in the housing or casing, supported thereby, connected thereto and encircling and rigidly secured to the sleeve, substantially as described.

2. In a centrifugal machine, the combination with a rotary-drum, and a drive-shaft therefor, of a cylinder or case having a bottom wall provided with a central opening, a housing arranged in the said central opening and having a lateral flange engaged with the bottom wall of the cylinder or case, a sleeve arranged in the housing, a spring located in the latter, supported thereby and rigidly connected to the sleeve and to the housing, and a cover-plate mounted on the flanged housing, substantially as described.

3. In a centrifugal machine, the combination with a rotary-drum, and a drive-shaft therefor, of a cylinder or case having a bottom wall, a flanged housing or casing secured to said bottom wall, a sleeve arranged centrally in the housing or casing, a removable bushing fitted into the sleeve and constituting a bearing for the drive-shaft, and a convolute spring located in the housing or casing, supported thereby, connected thereto and encircling and rigidly secured directly to the sleeve, substantially as described.

4. In a centrifugal machine, the combination with a rotary-drum, and a stationary cylinder or case, of a ring or annulus secured to the upper end of the drum, overhanging the same and arranged substantially horizontal, and a ring or annulus of greater diameter supported above the top edge of the cylinder or case, overhanging the same and providing a surrounding air exit, whereby the air currents descending through the drum, will not encounter the air currents ascending between the drum and the cylinder or case, substantially as described.

In testimony whereof I have hereunto set my hand in presence of two subscribing witnesses.

HAMILTON E. SMITH.
